United States Patent Office

Des. 192,334
Patented Mar. 6, 1962

192,334

CONTAINER FOR PULVERULENT MATERIAL OR THE LIKE

Clara Virginia Eicholtz, Midland, Mich., assignor to The Dow Chemical Company, Midland, Mich., a corporation of Delaware

Filed Feb. 20, 1961, Ser. No. 63,986

Term of patent 14 years

(Cl. D58—8)

FIGURE 1 is an elevational view of a container for pulverulent material or the like showing my new design;
FIGURE 2 is a top plan view thereof; and
FIGURE 3 is a perspective view thereof.

I claim:

The ornamental design for a container for pulverulent material or the like, as shown.
